The ornamental design for a keyboard for a handheld communication device, as shown and described.

DESCRIPTION

FIG. 1 is a perspective view of the keyboard for a handheld communication device of our new design;

FIG. 2 is a front view thereof;

FIG. 3 is a perspective view of a second embodiment of the keyboard for a handheld communication device of our new design, incorporating color contrast; and,

FIG. 4 is a front view of the design of FIG. 3.

The broken line showings of FIGS. 1-4 are for illustrative purposes only and form no part of the claimed design.

The evenly spaced shading at the top of the central keys and within letters and symbols in the second embodiment is intended to represent color contrast.
